GAUGING MACHINE

Warren S. Reynolds, Stratford, Conn., assignor to
 Remington Arms Company, Inc., Bridgeport,
 Conn., a corporation of Delaware

Application May 28, 1942, Serial No. 444,779

16 Claims.

(Cl. 209—88)

The present invention relates to an automatic inspection machine, particularly for the inspection of cartridges for the purpose of passing cartridges having a predetermined perfect profile and body length and rejecting cartridges having imperfections in profile and excessive body length. Cartridges from their nature must be extremely accurate in profile and body length in order to fit properly in the cartridge chamber of the gun, as projections upon the profile or excessive body length will cause jamming and serious damage.

It is an object of the invention to provide a machine of relatively great sensitivity, to the end that slight variations will cause the machine to be actuated to reject a cartridge having even very slight imperfections, and which at the same time includes positive mechanism having sufficient movement and force to effectually cooperate with the imperfect cartridge, and for this purpose it is proposed to provide a contact member arranged to be engaged by the cartridges, and in the case of imperfect cartridges to be moved thereby, whether the imperfection be substantial or of a relatively minute order, and to provide in cooperative relation therewith a cartridge gripping mechanism, between which and the contact means there is provided a movement multiplying mechanism by means of which a very slight movement of the contact means will be multiplied into a substantial movement of the gripping means.

A further object is to provide feeding means in the form of a gauge into which the cartridges are adapted to be fitted, cartridges having an oversized profile or projections thereon being prevented from fully engaging the gauge, and cartridges which are of an excessive length projecting from such gauge, and to provide feeding means in connection with such gauge which will cause it to successively pick up and feed cartridges into relation with the contact and gripping mechanism. It is further proposed to provide such feeding means which will yield during its feeding stroke, so that the forward feeding movement of the gauge will be arrested in the event of the projection of a cartridge therefrom for any distance up to substantially the full length of the cartridge, so that there will be no chance of excessive pressure being applied to the cartridge which might cause it to fire.

A further object is to provide mechanism for automatically feeding individual cartridges into aligned position to be picked up by the gauge mechanism.

A further object is to provide automatic means for ejecting the perfect cartridges from the gauge whereby they flow to a suitable receptacle, the imperfect cartridges being removed from the gauge by the gripping mechanism associated with the contact means, and whereby such imperfect cartridges are directed to another receptacle.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a plan view of the automatic inspection machine, according to the illustrated exemplary embodiment of the invention, portions of the bed plate support being broken away, and the reciprocating cartridge feeding gauge being shown at its forward projected feeding position with the cartridge in relation to the contact mechanism.

Fig. 2 is a side elevation.

Fig. 3 is an end elevation looking inwardly from the right-hand end of the machine as shown in Figs. 1 and 2.

Fig. 4 is a detail vertical sectional view, taken along the line 4—4 of Fig. 2, showing the cartridge feed guide and feed slide for feeding the cartridges into line with the gauging mechanism, this view being on a somewhat larger scale than Figs. 1 to 3.

Fig. 5 is a vertical longitudinal sectional view, taken along the line 5—5 of Fig. 4.

Fig. 6 is a plan view of the feed guide and feed slide as shown in Figs. 4 and 5.

Fig. 7 is a fragmentary view similar to Fig. 4 showing the feed slide in its projected position, wherein a cartridge is disposed in axial alignment with the reciprocating cartridge feed gauge.

Fig. 8 is a plan view, on a still larger scale, of the contact and cartridge gripping mechanism, showing the reciprocating cartridge feeding gauge in projected relation therewith, and showing a cartridge of perfect profile and body length engaged therein, the feed guide and slide mechanism being broken away for the sake of clearness.

Fig. 9 is a longitudinal vertical sectional view, taken along the line 9—9 of Fig. 8, and showing the reciprocating cartridge feeding gauge and the cartridge contact and gripping mechanism in side elevation.

Fig. 10 is an end elevation of the cartridge contact and gripping mechanism, looking out-

wardly from the left as shown in Fig. 9, the cartridge chute being shown in vertical section, taken along the line 16—10 of Fig. 9.

Fig. 11 is a plan view, similar to Fig. 8, showing the cartridge contact and gripping mechanism in its operative position as actuated by an over-length cartridge, and showing in dot-and-dash lines the open released position of the gripping mechanism and the partially retracted position of the cartridge feeding gauge.

Fig. 12 is a vertical sectional view, showing the cartridge feeding gauge in its fully retracted position wherein the passed cartridge of perfect profile and length is, seen in Fig. 8, is ejected.

Fig. 13 is a vertical transverse sectional view, taken along the line 13—13 of Fig. 12.

Fig. 14 is a vertical transverse sectional view, taken along the line 14—14 of Fig. 12.

Similar reference characters indicate corresponding parts throughout the several figures of the drawings.

The automatic inspection machine, according to the illustrated exemplary embodiment of the invention, consists of three main co-related mechanisms, namely, a reciprocating cartridge gauge mechanism, having a pocket shaped to correspond to a perfectly shaped exact length cartridge into which the cartridges are adapted to be fitted, a cartridge feed slide mechanism operating transversely to the reciprocatory axis of movement of the cartridge gauge, and adapted to feed the individual cartridges into longitudinal line with the gauge to be picked up thereby, and a contact and gripping mechanism adapted to be actuated by a cartridge of excessive length or imperfect profile and which does not fit properly in the feed gauge, and which is actuated to grip the neck end of the imperfect cartridge to remove it from the gauge.

Referring to the drawings, the inspection machine comprises a horizontal bed-plate support 10 provided with a substantially L-shape opening 11, into which are fitted parts of the cartridge feed slide mechanism and the inclined chute means, as will presently more fully appear, and an elongated rectangular slot opening 12, in which the slide member of the reciprocating cartridge gauge means is engaged, as will presently more fully appear.

Along the longitudinal sides of the slot opening 12, there are secured inwardly projecting parallel slide bearing strips 13—13, between which is slidably engaged a slide member 14 projecting above and below the support 10, a cylindrical opening 15 being provided in its lower portion in which is secured by a set-screw 16 a tubular cylindrical slide feed rod 16, extending longitudinally of the machine and having sliding bearing in a bearing bracket 17 secured to the underside of the support 10 at the outer end of the slot opening 12 and in a bearing bracket 18 secured to the underside of the support 10 near the inner end of the slot opening 12. This bracket 18 also mounts an adjustable stop screw 19, projecting rearwardly from the bracket and adapted to constitute a positive stop to the forward reciprocating movement of the cartridge gauge, its adjusted position being fixed by a locking lever 20 screwed upon its forwardly projecting end and bearing against the forward face of the bracket.

Adjacent and forwardly of the slide member 14, there is secured upon the rod 16 a block member 21, fixed to the rod by means of set screws 22—22 and provided at its underside with a transversely extending slide groove 23, in which

is slidably engaged a rectangular shaped slide shoe 24 pivotally mounted upon a stud 25 secured upon the forward end of a swinging feed lever 26 pivotally mounted at its other end upon a vertically disposed post 28 secured to and projecting downwardly from the support 10. Upon one side of the feed block member 21 there is provided a projecting stop lug 29 disposed in longitudinal line with the stop screw 19, and adapted to contact the screw 19 to limit and determine the forward position of movement of the reciprocating cartridge gauge.

Swinging movement is imparted to the lever 26 by means of an expandable link connected at one end to the lever 26 and at its other end to an eccentric drive disc 30, this expandable link connection comprising a relatively long rod member 31 having a clevis connection 32 with the lever 26, a relatively short rod member 33 having a pivot bearing 34 at its end pivotally connected with a stud pin 35 secured in eccentric relation to the disc 30, and a tubular member 36 telescopically engaged upon the rods 31 and 33 and provided with an elongated slot 37 through which a pin 38 secured to the rod 31 projects, and which is connected by a spring 39 to a pin 40 secured to the rod 33. Normally, the ends of the rods 31 and 33 abut each other within the tubular member 36, and during retracting movement of the reciprocating cartridge gauge from the full line position of the lever 26 to the dot-and-dash line position, as shown in Fig. 1, there is a positive rigid link connection between the eccentric disc 30 and the lever 26. However, in the projecting movement of the gauge, the link is adapted to expand in the event that there is any interruption in the projecting movement short of the full projected position, and such as may occur in the case of a cartridge of excessive length or imperfect profile. Such an imperfect cartridge may project from the end of the gauge in variable degree substantially up to the length of the cartridge, and in which case the movement of the gauge and the lever 26 is arrested while the eccentric disc 30 continues its movement causing the link to expand.

The eccentric disc 30 is provided with a downwardly extending hub 41 mounted upon the vertical shaft 42 of a power unit 43, comprising an electric motor and reduction gearing, and suspended from the underside of the bed plate support 10 upon an angular suspension bracket 44. This power unit drives cam means for operating the other cooperating mechanisms of the machine, as will hereinafter be more fully described, it being pointed out here that the machine operates through a complete cycle during each revolution of the eccentric disc 30.

At the upper end of the slide member 14, there is provided a cylindrical passage 45 having a longitudinal slit and clamping jaw portions 46 and 47 at one side, engaged by a clamping bolt 48 for rigidly securing within the passage 45 the outer end of the shank 49 of the cartridge gauge supporting socket head 50. The shank 49 is of tubular form and at its outer end is provided with a cylindrical reduced diameter bearing passage 51 in which is slidably engaged a fixed cartridge ejecting rod member 52. This rod member is mounted at its outer screw-threaded end in a bracket 53 secured upon the upper side of the support 10 outwardly of the end of the slot opening 12, and is adjustably fixed with respect to the bracket by means of a pair of lock nuts 54—54 screwed upon its threaded end portion

against each side of the bracket. At the other end, the cartridge ejecting rod is provided with a contact head 55 of smaller diameter than the passage in the tubular shank 49 and disposed therein in the projected position of the cartridge gauge, the gauge in its retracted position moving over the head 55 to a point where the head is exposed beyond the end of the gauge, for the purpose of ejecting a cartridge therefrom as shown in Fig. 12, and as will hereinafter more fully appear.

The cartridge gauge member 56 is of tubular form and is provided with a cartridge receiving pocket 57 shaped to exactly fit the contour of a perfect cartridge of proper length, the cartridge being engaged therein during the projecting movement of the gauge from the forward divergent end of the pocket. The gauge member is secured in the socket head 58 by means of a set screw 58, and obviously may be conveniently replaced by gauge members of various lengths and contours depending upon the particular type of cartridge being inspected. A slot 59 is provided in the gauge at one side near the outer end in which is engaged a straight end portion 60^a of a spring ring member 60 surrounding the gauge, this straight portion extending slightly into the cartridge receiving pocket for the purpose of frictionally retaining the cartridge in position, so that it will not be prematurely disengaged through inertia as the reciprocating cartridge gauge starts its retracting movement. Air holes 61 are provided in the wall of the gauge, so that air will not be entrapped therein as the cartridge is engaged.

Within the bed plate support opening 11, at the forward side of the longitudinal line of movement of the reciprocating cartridge gauge member, there is provided a cartridge feed slide mechanism for feeding the individual cartridges transversely into axial alignment with the longitudinal axis of the gauge member and in position to be picked up thereby. This mechanism comprises a fixture 62 in the form of a casting provided with attaching ears 63 projecting at each side and secured at the upper side of the support 10 at each side of the opening 11 by means of bolts 64. At the upper side of the support 10 the fixture 62 is provided with an inclined guide-way 65 provided with vertical parallel side walls 66 and 67 and upon which the cartridges are placed by hand or fed by means of suitable automatic means, so that they roll by gravity downwardly toward the lower end of the guide. For a short distance near the lower end the guide-way is disposed at a slightly increased angle of inclination, as at 68, and in order to prevent the foremost cartridges in the guide-way from accidentally becoming disengaged therefrom there are provided adjacent its forward end and upon the respective side walls 66 and 67 retaining angle members 69 and 70, the retaining member 69 being flat and projecting over the guide in parallel relation to accommodate the large ends of the cartridges, while the retaining member 70 is inwardly offset to accommodate the small ends of the cartridges.

At the underside of the support 10 the fixture 62 is provided with an upwardly inclined slide channel 71 in which a reciprocating cartridge feed slide 72 is engaged and retained by means of a cover plate 73 secured by screws 74. At its forward end, the slide is provided with a shouleder forwardly projecting ledge portion 75 disposed adjacent a slot 76 at one side of the slide

in which the end of the operating lever is engaged, as will presently more fully appear. Upon the ledge there is secured by screws 77 the flanged end 78 of the head-block 79 of the slide, the rearward surface of the flange 78 disposed within the slot 76 constituting a bearing for the end of the operating lever. The forward end of the head-block is provided with a projecting lip 80 which has its surface tangentially sloped into the concave forward end surface of the head which in the retracted position of the slide is disposed in line with the forward edge of the inclined cartridge guide-way, so that the cartridge rolls into the open-ended pocket provided by the lip 80 and the forward concave end of the head-block, to be thereupon fed into line with the reciprocating cartridge gauge upon projection of the feed slide.

In order to prevent the cartridges from accidentally slipping out of engagement with the slide before it is projected, there is provided within a slot 81 cut into the head-block an angular retaining trigger member 82, pivotally mounted upon a cross pin 83 and provided at its forward end with an upwardly curved finger formation which, as seen in Fig. 4, projects upwardly from the lip 80 of the head-block member **into engagement** with the foremost cartridge in the guide-way, holding it in a slightly raised position with respect to the slide member pocket, so that its upper surface is obstructed by the lower edge of the retaining member 69, and, consequently, the weight of the following cartridges within the guide-way will not force the foremost cartridge out of engagement with the slide. The trigger member is held in this cartridge retaining position by means of a stop-block 84, secured to the forward end of the cover plate 73 by screws 85, and which engages the downwardly projecting tail end 86 of the trigger member in the retracted position of the slide, causing the forward curved end of the trigger member to project into its retaining position, as seen in Fig. 4. As soon as the slide starts its projecting movement, the forward curved end of the trigger member is lowered, so that the forward cartridge lowers into engagement with the curved pocket surface and lip 80 of the head-block of the slide, the succeeding cartridge in the guide-way being at the same time lowered, so that it does not interfere with the forward projecting movement of the slide, the forward upper corner of the slide being moved beyond said next succeeding cartridge which thereupon is engaged with the upper surface of the slide and is supported thereby, as seen in Fig. 7. As the slide is projected the retaining trigger member drops below the surface of the lip 80, so that the cartridge which is carried by the slide into line with the longitudinal axis of the reciprocating gauge member is free to disengage from the feed slide as it retracts. In order to support the small end of the foremost cartridge in the guide-way there is provided adjacent the forward end of the wall 67 and in relation to the retaining member 70 a bracket 87 curved substantially like the curvature of the slide head-block member, but upon a smaller radius, to conform to the relatively smaller radius of the small end of the cartridge.

The transverse reciprocation of the feed slide and the longitudinal reciprocation of the cartridge gauge are so timed that as the cartridge is brought into line with the axis of the gauge the gauge has moved forwardly to a point where it engages over the small end of the cartridge

to pick it up from the feed slide, the feed slide thereupon retracting so that it is out of the path of the gauge as the latter continues its projecting movement and fully engages the cartridge.

The operating lever 88 for reciprocating the feed slide is pivotally mounted upon a depending bracket 90 secured at the underside of the support 10, being provided at one end with a roll-surface bearing end portion 91 engaged in the slot 76 of the slide through a notch 92 provided in the cover plate 73, and provided at its other end with a roller 93 riding upon a cam 94. This cam consists of a cylindrical collar member secured upon the hub 41 of the eccentric cam disc 30, the upper surface of the collar being suitably profiled to provide the rise and fall and dwell surfaces of the cam. A spring 95 is connected between a pin 96, provided upon the inner arm of the lever 88, and a bracket arm 97 secured to the lower end of the motor unit supporting hanger bracket 44, this spring yieldably retaining the roller 93 in engagement with the cam 94.

As the individual cartridges are picked up by the reciprocating cartridge gauge they are moved into relation with the contact and gripping mechanism, which in the case of a perfect cartridge of proper length fitting exactly into the gauge permits the gauge to carry the cartridge with it as it is retracted, whereupon this cartridge is ejected from the gauge upon complete retraction by means of the ejecting rod 55, as shown in Fig. 12, such cartridge dropping into the left-hand section 98 of an inclined chute member having its upper end disposed in the bed plate opening 12, and secured thereto by angle-attaching pieces 99 at each side thereof. In the case of an imperfect cartridge, having an oversize profile or excessive length, and which projects from the gauge in varying extent, the contact and gripping mechanism is actuated to grip the imperfect cartridge and remove it from the gauge as the latter is retracted, this cartridge being thereupon dropped into the right-hand section 100 of the inclined chute, so that the perfect and the imperfect cartridges are directed into separate receptacles.

The contact and gripping mechanism is provided at the end of the opening 11 in line with the longitudinal axis of the reciprocating cartridge gauge, and comprises a mounting block member 101 of rectangular form secured at its base flange portions 102 by means of bolts 103, this block being provided at its upper side and inwardly of its rearward edge with a T-shaped bearing portion 104 provided in its intermediate vertically disposed portion with a horizontal cylindrical passage 105 axially aligned with the longitudinal axis of the reciprocating cartridge gauge, and provided diametrically at each side with horizontal slots 106. Within the passage 105 there is slidably engaged a rod 107 provided upon its forward end with a cup-shaped contact button member 108, normally disposed in position to contact the large end of the cartridge carried by the gauge member in the projected position of the gauge member, as shown in Fig. 8. This rod has bearing at its rearward end in a bearing bracket 109, provided with a tubular bearing bushing 110 and secured at its base flange portions by bolts 111 to the support 10. Adjacent the rearward side of the block 101 a collar 112 is secured upon the rod 107, and in rearwardly spaced relation thereto there is secured upon the rod another collar 113, between which

and the bracket 109 there is provided a helical expansion spring 114 normally exerting forward pressure upon the rod to engage the collar 112 with the block 101, thereby limiting the projected position of the rod and the contact button 108. The collars may be adjusted upon the rod to respectively position the contact button in predetermined position and to change the tension of the spring 114, as desired.

10 This spring 114 is of sufficient strength that it will support the cartridge disposed in line with the reciprocating cartridge gauge as the gauge engages with the cartridge following the feeding of the cartridge into line with it by the feed slide mechanism, the cartridge moving from the feed slide as it is first engaged by the gauge to a point where it contacts the button 108, being then supported by the button as the gauge member completes its projecting movement into fitting engagement with the cartridge. This support of the spring 114 is just sufficient to overcome the frictional resistance that is set up as the cartridge is engaged by the gauge member. However, in the event that the cartridge is of excessive length so that it cannot fully engage the gauge member, or in the event that its profile is such that it cannot fully engage the gauge member, the spring 114 will yield to allow the contact button 108 and the rod 107 to move inwardly up to the predetermined distance determined by the adjustable stop screw 115 mounted in a bracket 116 secured at its base flange portion upon the support 10 adjacent the bearing bracket 109 by means of bolts 117. The pressure of the spring 114 is therefore in excess of the frictional resistance set up through normal engagement of a perfect cartridge with the reciprocating cartridge gauge, but is less than the opposing force of the spring 39 of the expansible link member 30 which drives the gauge. The expansible link member functions to allow the projecting movement of the gauge to be arrested when the projection of an excessive length cartridge or an irregular profile cartridge from the gauge member is greater than the limited movement of the rod 107, so that as the eccentric cam 30 continues its rotation the link member is expanded and simply exerts projecting pressure upon the gauge to hold the cartridge against the contact button 108.

Upon the sides of the block 101, there are provided a pair of opposed gripping finger levers 118, pivotally mounted upon pivot pins 119 rearwardly of the T-shaped bearing formation 104, and supported slidably in the slots 106 at each side, and extending forwardly therefrom beyond the contact button 108, where they are provided at their forward ends with inwardly extending claw-ends 120. These claw-ends are adapted to engage diametrically opposed slots 121 cut into the forward end of the reciprocating cartridge gauge 56 substantially in line with the recessed neck portion 122 of the cartridge A so that by inward movement of the gripping finger levers these claw-ends will engage within the recess 122 of the cartridge. A spring 123 is connected between posts 124 provided upon the finger levers and tends to draw them inwardly toward each other. Normally, the finger levers are prevented from moving inwardly to engage the recess 122 by means of a pair of shouldered pins 125, respectively mounted in the levers and abutting diametrically upon each side of a sleeve member 126 slidably mounted on the rod 107 between the contact button 108 and the mounting block 101.

These pins are each adjustable inwardly and outwardly in a horizontal slot opening 127 in the finger lever, being fixed in adjusted position by means of a tightening screw 128 having its head disposed at the upper side of the slotted portion of the lever at one side of the pin and being screwed into the lower side, tightening action of the screw binding the slotted portion of the lever against the pin. The point of engagement of the pins 125 with the sleeve 126 is relatively close to the forward side of the sleeve so that a relatively small movement of the sleeve in a rearward direction will cause it to disengage from the pins, whereupon the levers 118 move inwardly into cartridge gripping relation under the action of the spring 123 connected between them.

The sleeve 126 is adapted to be actuated rearwardly to finger lever releasing position through a movement multiplying means actuated by the rearward movement of the contact button 108 and rod 107, so that a very slight rearward movement of this rod 107 will cause a substantially greater rearward movement of the sleeve 126, and consequently there will be a positive disengagement of the sleeve from the pins 125 upon any rearward movement of the contact button, however slight. This means comprises a movement multiplying lever 129 having a long arm and a short arm and pivotally mounted upon a supporting post 130, the short arm of this lever being engaged with the rearward side of the collar 112 fixed upon the rod 107, while the long arm is connected by a link 131 to the short arm of a second movement multiplying lever 132 pivotally mounted upon a supporting post 133, the long arm of this second lever being provided at its end with a slot 134 engaged by a downwardly projecting pin 135 provided upon the flat underside of the sleeve 126. Between the sleeve 126 and the mounting block 101 there is provided a helical expansion spring 136 engaged around a tubular collar extension 137 of the sleeve, this spring exerting forward pressure upon the sleeve and through the lever 132 and link 131 exerting pressure upon the lever 129 in counter-clockwise direction to press its short arm against the collar 112.

During each operative cycle the gripping finger levers 119 are swung outwardly from their normal position as shown in Fig. 8 to the open position as shown in dot-and-dash lines in Fig. 11, or equally, this opening movement being for the dual purpose of releasing the end of the cartridge gripped by the fingers in the event that the mechanism has been operated to the gripping position, as shown in Fig. 11, and moving the pins 125 to a position where they will be clear of the sleeve 126 to allow it to resume its normal projected position under the pressure of the spring 136, the closing movement of the gripping finger levers being limited by engagement of the pins 125 with the sleeve 126.

For the purpose of bringing about this opening and closing movement, there is provided a cam lever 138 mounted upon the upper end of a vertical shaft 139 journaled in a bearing bushing 140 secured in the support 10, this lever being provided at its forward end with a wedge-shaped cam plate portion 141 having its inclined side edges disposed between the posts 124 to which the spring 123 is connected. Upon the lower end of the shaft 139 there is secured a lever arm 142 provided at its end with a roller 143, which rides upon the peripheral cam surface 144 of the eccentric cam disc 30 and is yieldably pressed into engagement therewith by a spring 145 connected

between a post 146 provided upon the lever arm 142 and a post 147 secured upon the under side of the support 10. The peripheral cam surface 144 has a rise which at one point in the operative cycle causes the lever arm 142 and the cam lever arm 138 to swing in clockwise direction to the position shown in dot-and-dash lines in Fig. 11, engaging the cam plate portion 141 between the posts 123 and causing the gripping finger levers 119 to be moved to open position.

Summarizing the operation of the machine, the cartridges A are fed into the feed slide 65 where they move by gravity into the pocket of the reciprocating slide 72, the foremost cartridge being retained therein by the trigger lever 82, which in cooperation with the retaining member 69 prevents this foremost cartridge from accidentally disengaging from the feed slide through the weight of the following cartridges in the feed guide. The feed slide is projected to the position shown in Fig. 7 to align the cartridge with the longitudinal axis of the reciprocating cartridge gauge 56, which starts its projecting movement in time to engage the cartridge before retraction of the feed slide, the feed slide retracting in time to clear the cartridge gauge as the latter continues its projecting movement. The large end of the cartridge engages the contact button 108, which acts as an abutment therefor as the cartridge engages the gauging pocket 57 of the gauge, the spring 114 being sufficiently strong to resist movement of the contact button 108 and rod 107 during the normal engagement of the cartridge with the gauge.

The projected position of the gauge is determined by the stop screw 19, and in the case of a cartridge of proper length and perfect profile fitting exactly in the gauge pocket, the gauge will move to its fully projected position and the cartridge will engage the contact button 108, as shown in Fig. 8, without actuating the contact button to cause actuation of the cartridge gripping levers. Upon retraction of the gauge, the cartridge will be carried with it in retracting direction to the point where the ejecting rod 52 ejects it from the gauge as shown in Fig. 12, this perfect cartridge dropping into the chute 98.

In the case of an over-length cartridge, or a cartridge of imperfect profile which will not fully engage the gauge and will therefore project therefrom, such cartridge will cause the contact button 108 and rod 107 to be pressed inwardly, and this inward movement, however slight, will through the movement-multiplying levers 129 and 132 cause the sleeve 126 to be moved inwardly to a substantially greater extent than the movement of the contact button, causing the pins 125 to be positively released and allowing the gripping levers 118 to swing inwardly under the action of the spring 123, so that the claw ends 120 grippingly engage the neck 122 of the cartridge, as shown in Fig. 11. Upon retraction of the gauge this imperfect cartridge is restrained and disengaged from the gauge, so that it drops into the chute 100.

In the case of a cartridge which is of such excessive length or irregularity that the contact button 108 and rod 107 are pressed inwardly to the point where the stop screw 115 is engaged, 70 and the cartridge gauge 56 is arrested in its projecting movement short of its full projected position determined by the stop screw 19, the expansion link connecting the lever 26 to the eccentric cam disc 30 expands as swinging movement of the lever is stopped and the cam con-

tinues its normal cycle of rotation, so that irrespective of the projection of the cartridge from the gauge there is no likelihood of excessive pressure being applied to the cartridge, or of jamming or damage to the machine.

During each cycle of operation, the cam lever 128 is actuated, causing the gripping levers 118 to swing outwardly to the dot-and-dash line position shown in Fig. 11, thus allowing the sleeve 126 to resume its normal position between the pins 125, as shown in Fig. 8. In the case of a perfect cartridge, the gripping levers will simply move to this dot-and-dash line position from the normal position shown in Fig. 8, whereas in the case of an imperfect cartridge, which actuates the contact and gripping mechanism, the gripping levers move to the dot-and-dash line position from the contracted gripping position shown in Fig. 11.

The form of the invention illustrated in the drawings and described herein is typical and illustrative only, and it is evident that the invention is capable of embodiments in other forms, all falling within the scope of the appended claims.

What is claimed is:

1. In an inspection machine for gauging articles, a reciprocating gauge having rectilinear movement and having an article receiving gauging pocket, means arranged to limit the projecting movement of said gauge to a predetermined point, movable contact means in axial alignment with said gauge arranged to be engaged and moved in the projected position of said gauge by the end of an abnormally projecting article carried thereby, and means arranged to be actuated by movement of said contact means to restrain said movement-causing abnormal article to cause its disengagement from said gauge upon retracting movement of the latter.

2. In an inspection machine for gauging articles, a reciprocating gauge having rectilinear movement and having an article receiving gauging pocket, means arranged to limit the projecting movement of said gauge to a predetermined point, movable contact means in axial alignment with said gauge arranged to be engaged and moved in the projected position of said gauge by the end of an abnormally projecting article carried thereby, article-feeding means arranged in a direction transverse to the reciprocating axis of said gauge adapted in the retracted position of said gauge to feed said articles transversely into longitudinal line therewith to be picked up thereby upon projecting movement thereof, means to reciprocate said gauge from its retracted position to said predetermined gauging point limit so as to pick up an article from a position in line of movement of the gauge and carry said article toward said contact means, and means arranged to be actuated by movement of said contact means to restrain said movement-causing abnormal article to cause its disengagement from said gauge upon retracting movement of the latter.

3. In an inspection machine for gauging articles, a reciprocating gauge having rectilinear movement and having an article receiving gauging pocket, means arranged to limit the projecting movement of said gauge to a predetermined point, movable contact means in axial alignment with said gauge arranged to be engaged and moved in the projected position of said gauge by the end of an abnormally projecting article carried thereby, article gripping means, and

movement-multiplying means cooperatively arranged between said contact means and said gripping means adapted to be actuated by movement of said contact means to cause said gripping means to grip said movement-causing abnormal article to cause its disengagement from said gauge upon retracting movement of the latter.

4. In an inspection machine for gauging articles, a reciprocating gauge having rectilinear movement and having an article receiving gauging pocket extending axially inwardly from its forward end, a pair of article-receiving means arranged in side-by-side relation beneath the reciprocating gauge between the projected and retracted points of its forward end, movable contact means in axial alignment with said gauge arranged to be engaged and moved in the projected position of said gauge by the end of an abnormally projecting article carried thereby, means arranged to be actuated by movement of said contact means to restrain said movement-causing abnormal article to cause its disengagement from said gauge upon retracting movement of the latter, whereby said article drops into said article-receiving means adjacent the projected point of said gauge, and ejection means in proximity to said retracted point adapted to eject from said gauge an article carried thereby in retracting direction, whereby said last-mentioned article drops into said article-receiving means adjacent said retracted point of said gauge.

5. In an inspection machine for gauging articles, a reciprocating gauge having rectilinear movement for a distance equal in length to at least twice the length of said articles and having an article receiving gauging pocket extending axially inwardly from its forward end, a pair of article-receiving means arranged in side-by-side relation beneath the reciprocating gauge between the projected and retracted points of its forward end, movable contact means in axial alignment with said gauge arranged to be engaged and moved in the projected position of said gauge by the end of an abnormally projecting article carried thereby, means arranged to be actuated by movement of said contact means to restrain said movement-causing abnormal article to cause its disengagement from said gauge upon retracting movement of the latter, whereby said article drops into said article-receiving means adjacent the projected point of said gauge, and ejection means in proximity to said retracted point adapted to eject from said gauge an article carried thereby in retracting direction, whereby said last-mentioned article drops into said article-receiving means adjacent said retracted point of said gauge.

6. In an inspection machine for gauging articles, a tubular reciprocating gauge having rectilinear movement and having an article receiving gauging pocket extending axially inwardly from its forward end, a pair of article-receiving means arranged in side-by-side relation beneath the reciprocating gauge between the projected and retracted points of its forward end, movable contact means in axial alignment with said gauge arranged to be engaged and moved in the projected position of said gauge by the end of an abnormally projecting article carried thereby, means arranged to be actuated by movement of said contact means to restrain said movement-causing abnormal article to cause its disengagement from said gauge upon retracting movement of the latter, whereby said article drops into said

article-receiving means adjacent the projected point of said gauge, and a fixed ejection rod disposed in said tubular gauge having its forward end in proximity to said retracted point adapted to eject from said gauge an article carried thereby in retracting direction, whereby said last-mentioned article drops into said article-receiving means adjacent said retracted point of said gauge.

7. In an inspection machine for gauging articles, a reciprocating gauge having rectilinear movement and having an article receiving gauging pocket, yieldable drive means connected to said gauge to impart reciprocating movement thereto adapted to yield during projecting movement of said gauge, yieldable contact means in axial alignment with said gauge arranged to be engaged in the projected position of said gauge by the end of an article carried thereby, and to be yieldably moved by the end of an abnormally projecting article carried thereby, the resistance to yielding of said contact means being less than the resistance to yielding of said drive means, article feeding means arranged in a direction transverse to the reciprocating axis of said gauge adapted in the retracted position of said gauge to feed said articles transversely into longitudinal line with said gauge to be picked up thereby upon projection of said gauge and whereby continued projecting movement of said gauge causes said picked up article to be abutted at one end by said contact means as said article engages said gauging pocket of said gauge, and means arranged to be actuated by movement of said contact means to restrain said movement-causing abnormal article to cause its disengagement from said gauge upon retracting movement of the latter.

8. In an inspection machine for gauging articles, a reciprocating gauge having rectilinear movement and having an article receiving gauging pocket, movable contact means in axial alignment with said gauge arranged to be engaged and moved in the projected position of said gauge by the end of an abnormally projecting article carried thereby, stop means arranged to limit the movement of said contact means, means arranged to be actuated by movement of said contact means to restrain said movement-causing abnormal article to cause its disengagement from said gauge upon retraction movement of the latter, a swinging lever connected to said reciprocating gauge to drive it, an eccentric drive means, and a yieldably expansible drive link between said eccentric drive means and said lever adapted to have expansion movement upon stoppage of the projecting movement of said reciprocating gauge short of its fully projected position.

9. In an inspection machine for gauging articles, a reciprocating gauge having rectilinear movement and having an article receiving gauging pocket, movable contact means in axial alignment with said gauge arranged to be engaged and moved in the projected position of said gauge by the end of an abnormally projecting article carried thereby, an article feeding guide arranged in a direction transverse to the reciprocating axis of said gauge, a reciprocating article feeding slide having a pocket end adapted to receive individual articles from said guide and through projecting movement to feed said articles into longitudinal line with the reciprocating axis of said gauge to be picked up thereby upon projecting movement thereof, means to reciprocate said gauge from a retracted position to a position near the movable contact means so as to pick up an

article from said feed slide pocket, and means arranged to be actuated by movement of said contact means to restrain said movement-causing abnormal article to cause its disengagement from said gauge upon retracting movement of the latter.

10. In an inspection machine for gauging articles, a reciprocating gauge having rectilinear movement and having an article receiving gauging pocket, movable contact means in axial alignment with said gauge arranged to be engaged and moved in the projected position of said gauge by the end of an abnormally projecting article carried thereby, an article feeding guide arranged in a direction transverse to the reciprocating axis of said gauge, a reciprocating article feeding slide having a pocket end adapted to receive individual articles from said guide and through projecting movement to feed said articles into longitudinal line with the reciprocating axis of said gauge to be picked up thereby upon projecting movement thereof, article retaining means at the end of said guide, for engaging the articles at their upper sides, an article retaining trigger member movably carried by said pocket end of said slide, means adapted in the retracted position of said slide to engage said trigger means to project it into retaining relation, whereby in cooperation with said article retaining means it prevents disengaging movement of an article from said pocket end of said slide, said trigger means adapted to be retracted into article releasing position upon projecting movement of said slide, and means arranged to be actuated by movement of said contact means to restrain said movement-causing abnormal article to cause its disengagement from said gauge upon retracting movement of the latter.

11. In an inspection machine for gauging articles, a movable gauge having to-and-fro movement and having an article receiving gauging pocket, means arranged to limit the projecting movement of said gauge to a predetermined point, movable contact means in alignment with said gauge arranged to be engaged and moved in the projected position of said gauge by the end of an abnormally projecting article carried thereby, article gripping means disposed outwardly at opposed sides of said contact means normally out of engagement with said article and adapted to be moved inwardly into gripping engagement therewith, and movement-multiplying means cooperatively arranged between said contact means and said gripping means adapted to be actuated by movement of said contact means to cause said gripping means to grip said movement-causing abnormal article to cause its disengagement from said gauge upon retracting movement of the latter.

12. In an inspection machine for gauging articles, a movable gauge having to-and-fro movement and having an article receiving gauging pocket, means arranged to limit the projecting movement of said gauge to a predetermined point, a fixed bearing member, a slidable contact rod mounted in said bearing member having a contact end in alignment with said gauge arranged to be engaged and moved in the projected position of said gauge by the end of an abnormally projecting article carried thereby, spring means exerting projecting pressure on the contact rod, stop means associated with said rod to limit its projecting movement, article gripping means disposed outwardly at opposed sides of said contact rod normally out of engagement

with said article and adapted to be moved inwardly into gripping engagement therewith, and movement-multiplying means cooperatively arranged between said contact rod and said gripping means adapted to be actuated by movement of said contact rod to cause said gripping means to grip said movement-causing abnormal article to cause its disengagement from said gauge upon retracting movement of the latter.

13. In an inspection machine for gauging articles, a movable gauge having to-and-fro movement and having an article receiving gauging pocket, means arranged to limit the projecting movement of said gauge to a predetermined point, a fixed bearing member, a slidable contact rod mounted in said bearing member having a contact end in alignment with said gauge arranged to be engaged and moved in the projected position of said gauge by the end of an abnormally projecting article carried thereby, spring means exerting projecting pressure on the contact rod, stop means associated with said rod to limit its projecting movement, article gripping levers disposed outwardly at opposed sides of said contact rod normally out of engagement with said article and adapted to be moved inwardly into gripping engagement therewith, a spring connected between said gripping levers adapted to exert inward force thereon, an abutment sleeve member slidably mounted on said rod normally engaged by said gripping levers to retain them in open position, and movement-multiplying means cooperatively arranged between said contact rod and said sleeve member adapted to be actuated by movement of said contact rod to cause said sleeve to be moved to disengage it from said gripping levers, whereby said gripping levers move inwardly to grip said movement-causing abnormal article to cause its disengagement from said gauge upon retracting movement of the latter.

14. In an inspection machine for gauging articles, a movable gauge having to-and-fro movement and having an article receiving gauging pocket, means arranged to limit the projecting movement of said gauge to a predetermined point, a fixed bearing member, a slidable contact rod mounted in said bearing member having a contact end in alignment with said gauge arranged to be engaged and moved in the projected position of said gauge by the end of an abnormally projecting article carried thereby, spring means exerting projecting pressure on the contact rod, stop means associated with said rod to limit its projecting movement, stop means arranged to limit the retracting movement of said contact rod, article gripping levers disposed outwardly at opposed sides of said contact rod normally out of engagement with said article and adapted to be moved inwardly into gripping engagement therewith, a spring connected between said gripping levers adapted to exert inward force thereon, an abutment sleeve member slidably mounted on said rod normally engaged by said gripping levers to retain them in open position, and movement-multiplying means cooperatively arranged between said contact rod and said sleeve member adapted to be actuated by movement of said contact means to cause said sleeve to be moved to disengage it from said gripping levers, whereby said gripping levers move inwardly to grip said movement-causing abnormal article to cause its disengagement from said gauge upon retracting movement of the latter.

15. In an inspection machine for gauging arti-

cles, a movable gauge having to-and-fro movement and having an article receiving gauging pocket, means arranged to limit the projecting movement of said gauge to a predetermined point, a fixed bearing member, a slidable contact rod mounted in said bearing member having a contact end in alignment with said gauge arranged to be engaged and moved in the projected position of said gauge by the end of an abnormally projecting article carried thereby, spring means exerting projecting pressure on the contact rod, stop means associated with said rod to limit its projecting movement, article gripping levers disposed outwardly at opposed sides of said contact rod normally out of engagement with said article and adapted to be moved inwardly into gripping engagement therewith, a spring connected between said gripping levers adapted to exert inward force thereon, an abutment sleeve member slidably mounted on said rod normally engaged by said gripping levers to retain them in open position, and movement-multiplying means cooperatively arranged between said contact rod and said sleeve member adapted to be actuated by movement of said contact rod to cause said sleeve to be moved to disengage it from said gripping levers, whereby said gripping levers move inwardly to grip said movement-causing abnormal article to cause its disengagement from said gauge upon retracting movement of the latter, and cam means arranged to cooperate with said gripping levers to move them outwardly during each cycle of to-and-fro movement of said gauge.

16. In an inspection machine for gauging articles, a movable gauge having to-and-fro movement and having an article receiving gauging pocket, means arranged to limit the projecting movement of said gauge to a predetermined point, a fixed bearing member, a slidable contact rod mounted in said bearing member having a contact end in alignment with said gauge arranged to be engaged and moved in the projected position of said gauge by the end of an abnormally projecting article carried thereby, spring means exerting projecting pressure on said contact rod, stop means associated with said rod to limit its projecting movement, article gripping levers disposed outwardly at opposed sides of said contact rod normally out of engagement with said article and adapted to be moved inwardly into gripping engagement therewith, a spring connected between said gripping levers adapted to exert inward force thereon, an abutment sleeve member slidably mounted on said rod normally engaged by said gripping levers to retain them in open position, and movement-multiplying means cooperatively arranged between said contact rod and said sleeve member adapted to be actuated by movement of said contact rod to cause said sleeve to be moved to disengage it from said gripping levers, whereby said gripping levers move inwardly to grip said movement-causing abnormal article to cause its disengagement from said gauge upon retracting movement of the latter, said movement multiplying means comprising a movement-multiplying lever arranged to be actuated by retracting movement of said contact rod, a movement-multiplying lever connected to said sleeve member, a link connection between said movement-multiplying levers, and spring means cooperating with said sleeve member exerting pressure thereon to yieldably retain it in its normal gripping lever supporting position.

WARREN S. REYNOLDS.
